FABRIC CENTERING DEVICE

Angelo Andreotto, Clifton, N. J., assignor to Botany Worsted Mills, Passaic, N. J., a corporation of New Jersey

Application June 6, 1942, Serial No. 446,081

5 Claims. (Cl. 271—2.6)

The object of the present invention is to provide means for centering lengths of fabric being fed to washing, finishing or other fabric treating apparatus. Often the lengths of fabric are led to the feeding mechanism when roughly folded, stacked or piled, and it is necessary for an operator to constantly watch the fabric as it is led to the feeding mechanism in order to keep the fabric centered. It is sometimes necessary to exert upon the moving web of fabric a lateral shifting force continuing over substantial periods of time, due to a number of different factors including the character of the weave. By means of the present invention, manual control of the movement of the fabric may be eliminated and a device is provided which will meet every condition required for centering fabrics of all kinds.

The invention will be described with reference to the accompanying drawings in which—

Figure 1 is a view in end elevation, partly in section, illustrating an embodiment of the invention, looking in the direction of arrows 1—1, Figure 2.

Figure 2 is a fragmentary front elevation illustrating the elements shown in Figure 1.

Figure 3 is a fragmentary plan view of the embodiment.

Figure 4 is a fragmentary plan view showing two of the centering rollers, their yoke carriers and the bar which swings the carriers.

Figure 5 is a perspective view showing one of the centering rollers and the mounting and swinging means therefor.

Figure 6 is a perspective view, illustrating the frictional actuator for the centering rollers, the means for adjusting the limit of moving thereof.

Figure 7 is a vertical section taken through the frictional actuator on the line 7—7, Figure 3.

Figure 8 is a wiring diagram for the reversible motor which drives the frictional actuator.

Referring to the drawings, I have shown at 1 a framework comprising two spaced standards connected near the top thereof by an angle frame member 1x. One of the standards carries a bracket 2 supporting a reversible motor 3, the shaft 3x of the latter driving a pulley 4 which receives a belt 5 led over a driven pulley 6 on a shaft 7 suitably carried by bearing members connected to the frame.

Carried by shaft 7 is a worm 8 which drives a worm wheel 9 on a shaft 10. Loosely mounted on shaft 10 is an actuator disk 11. Keyed or otherwise secured to shaft 10 at opposite sides of the actuator disk are friction drive disks 12. These friction drive disks are preferably faced

with rubber or other suitable frictional material 12, Figure 7.

In order to adjust the degree of functional grip between the actuator disk 11 and the frictional drive disk 12, the outer end of shaft 10 may be threaded to receive an adjusting nut 13.

Actuator disk 11 carries an arm 11x pivotally connected to the yoke end 14x of a link 14 which in turn is pivoted to the yoke end of an actuator bar 15 for the centering rollers now to be described.

Carried by the transversely extending angle frame 1x at the top of the framework is a plate 16, and in straight line arrangement the plate has pivoted thereto a plurality of U-shaped centering roll carriers 17, each carrier having welded or otherwise secured thereto a lever 17x pivoted to actuator bar 15. The arms of each carrier 17 support a shaft 18 for a centering roller 19. The pivots for the centering roller carriers are indicated at 20.

At the front of the device is a guide roller 21 which receives the web of fabric indicated at F. Roller 21 is mounted in bearing bosses 22x at the ends of arms 22 projecting from the framework. The web of fabric then passes to and over the centering rollers 19 and passes over a rearwardly positioned roller 23, Figure 1.

Secured upon cross frame member 1x is an arm 24 formed at its end with a sleeve 24x which adjustably receives supporting shaft 25 for a switch device. The switch device in the present embodiment comprises a box-like housing 26 having an aperture in its base for the movement of the switch arm 27 pivoted on bracket 28x. Switch arm 27 acts by gravity to move a contact finger 27x into engagement with a circuit-closing contact 28, and the finger is also positively movable against gravity by the web of fabric in a reverse direction to carry contact finger 27x into engagement with a second circuit-closing contact 29. Contact finger 27x normally lies between contacts 28 and 29 through engagement by a properly centered web of fabric F with the switch arm 27xx.

The motor 3 is reversible. As shown by the diagram, Figure 8, the power feed line P is connected to both of the positive poles of the motor, whereas one pole at the negative side is connected by line A to switch contact 28 and the second negative pole is connected by line B to switch contact 29, the contact finger 27x being grounded. Thus when contact finger 27x engages contact 28 the motor will rotate in a given direction, and when contact finger 27x engages

contact 29 the motor will rotate in a reverse direction.

As the web of fabric is pulled over the roller 19 it will, if properly centered, maintain a light pressure on switch arm 27 and will hold it against gravitational action intermediate contacts 28 and 29 and the motor will remain idle. Should the moving web of fabric creep to the right, switch arm 27 will carry finger 27x into engagement with contact 29 and the motor will rotate to turn worm wheel 9 clockwise thus shifting the fabric web to the left until finger 27x moves to a point intermediate the contacts. In many cases there will be a lateral creeping of the fabric which is progressive over a considerable period of time, and, in such case, the automatic adjustment will, throughout such period, maintain that part of the web which passes off the roller 21 properly centered with respect to roller 23 or any other receiving elements. Should the web creep to the left the gravitational action of switch arm 27xx will cause finger 27x to engage contact 28 and a reverse action will take place.

Means are provided for limiting the angular movement of the centering rollers 19, such means being illustrated in Figure 6 more particularly. It will be seen that arm 11x of the actuator disk lies adjacent an arcuate bracket 30 which is fixed to the frame. The bracket is formed with a plurality of apertures to receive opposed stops 31. In accordance with the spacing of these stops the movement of actuator disk 11 is limited in either direction. Hence the maximum angle of movement of the centering rollers may be controlled.

By means of the invention, it is unnecessary for an operator to watch and manipulate the fabric web as it is led to the initial roller of the mechanism, the apparatus automatically centering the web of fabric by exerting thereon a lateral shifting force in either of two directions, which force will continue until the web is properly centered, and if the web has a constant tendency to creep, the corrective shifting force will be constantly applied.

Having described my invention, what I claim and desire to secure by Letters Patent is as follows:

1. In fabric centering devices and in combination with means for guiding a web of fabric, of a plurality of individually pivoted and normally co-axial centering rollers over which the web of fabric may be led, power means for angularly adjusting said centering rollers in a given direction and in a reverse direction, and means adapted to be engaged and moved by the web of fabric for controlling the direction of individual pivotal movements of said centering rollers in accordance with creeping movements of the web of fabric transversely of its longitudinal axis whereby the

rollers are moved into and out of co-axial relationship.

2. In fabric centering devices and in combination with means for guiding a web of fabric, of a plurality of centering rollers over which the web of fabric may be led, a pivoted carrier for each roller the carriers normally holding the rollers in co-axial relationship, a reversible motor and connections with each pivotal carrier for swinging the same in reverse directions, and means adapted to be engaged and moved by the web of fabric for controlling the direction of movement of said pivoted carriers in accordance with creeping movements of the web transversely of its longitudinal axis whereby the rollers are moved into and out of co-axial relationship.

3. In fabric centering devices and in combination with means for guiding a web of fabric, of a plurality of centering rollers over which the web of fabric may be led, pivotal carriers for each roller the carriers normally holding the rollers in co-axial relationship, a reversible electric motor, and connections between the motor and each of said carriers for swinging the same to carry the rollers into and out of co-axial relationship, two electrical circuits, one leading to the motor for operation thereof in a given direction and one leading to the motor for operation thereof in a reverse direction, and a movable circuit-closing device adapted to selectively close the two circuits, said device including an arm adapted to lie in contact with an edge of the web of fabric and to be moved thereby in accordance with creeping movements of the web of fabric transversely of its longitudinal axis.

4. In fabric centering devices and in combination with means for guiding a web of fabric, of a set of centering rollers over which the web of fabric may be led, pivoted carriers for the centering rollers, a reversible electric motor, and connections between the same and a bar connected to the carriers for swinging the same in reverse directions thereby carrying the rollers into and out of co-axial relationship, two electrical circuits leading to the motor, one for controlling the rotation thereof in one direction and one for controlling the rotation thereof in an opposite direction, and a switch device for selectively closing the two circuits including a switch-actuating member adapted to be engaged by an edge portion of the web of fabric and to be moved in accordance with creeping movements of the web of fabric transversely of its longitudinal axis.

5. In fabric centering devices constructed in accordance with claim 2, a frictionally driven actuator disk forming a part of the connections between the pivotal and reversible motor, and means for adjusting the limit of movement of said frictional disk in each of two directions.

ANGELO ANDREOTTO.
